UNITED STATES PATENT OFFICE.

HAROLD M. COOPER, OF MARSHALLTOWN, IOWA.

GASOLINE RESERVE.

Application filed January 8, 1926. Serial No. 80,108.

This invention relates generally to means for providing a reserve capacity in a liquid holding tank. In the form illustrated herewith it is shown as applied to the fuel tank 5 of an automotive vehicle in which means are provided for retaining a quantity of fuel within the tank to provide a reserve capacity. In the particular arrangement embodied in the invention, in normal operation the fuel tank cannot be entirely drained. When it has been drained to the normal lowest level, the operator may thereafter change the setting of his reserve fuel valve and thereafter draw upon his reserve 15 capacity. It is one of the objects of the invention to provide means for carrying out the above operation. Another object is to provide in a valve itself a construction whereby any ordinary tank without any 20 construction may be arranged to have a reserve fuel capacity. Another object is to provide such a valve which can be inserted readily in connection with a standard fuel tank and fuel supply system without the 25 necessity of remachining or altering any of the usual parts already in place. Other objects will appear from time to time throughout the specification and claim.

My invention is illustrated more or less 20 diagrammatically in the accompanying drawing; wherein:

Figure 1 is a fragmentary side elevation of an automobile with parts in section;

Figure 2 is a side elevation of a valve 35 showing the operating wheel;

Figure 3 is a vertical cross section showing the valve;

Figure 4 is a transverse section taken on line 3—3 of Figure 3.

Like parts are designated by like characters throughout.

The automobile is indicated generally at A. B is a fuel tank. C is an engine. D is a sediment pocket or bulb through which 45 the fuel flows and it is controlled by a valve which is indicated at E¹. D² is a portion of a fuel line running to the carburetor of the engine. These details will not be further illustrated as they form no particular part of the present invention.

My invention is not limited to an association with them. My invention is indicated in Figure 1 generally at E. As shown in greater detail in later figures, it 55 is formed of a generally straight tubular body E¹ having at one end an inlet opening

E² and being threaded about said end as at E³. It is provided at its other end with an outlet opening E⁴ which is interiorly threaded as at E⁵. Connected with the tubular part E¹, between its ends and communicating with the tubular passage therethrough, is with a vertically extending generally tubular body E⁶ which is threaded exteriorly at its open upper end as at E⁷.
60

Extending centrally of this vertically disposed tubular body is a partition wall F which stops short of the top of the member E⁶, and thus extends downward and across the tubular member E¹ being provided with a generally cylindrical enlargement F¹ which has an inlet opening F² and an outlet opening F³ such openings being inclined with the tubular opening or passage through the part E¹.
70

Within the bore of the cylindrical enlargement F¹ is a valve G which has through it a passage G¹ adapted when in one position to register with openings F² and F³. This valve is provided with a reduced extension G² on which is fastened a limiting member G³ and on which is also fastened a controlling and operating wheel G⁴. This wheel may have an indicator such as the arrow G⁵. G⁶ is a packing about the valve 80 reduced portion G². G⁷ is a packing retaining gland by means of which the valve is held in position, the packing is compressed and displacement of the parts and leakage 85 of the fluid within the valve is prevented.
90

H is a pressure escape tube, fastened to the upper end E⁷ of the part E⁶ and held thereto by means of a nut H¹. H² H² are spacing washers. The tube H is preferably provided with a downwardly bent upper end 95 H³.

I is a projection connected to the tubular portion E¹ of the valve. As shown in Figure 2 it is generally horizontal. I¹ is a similar projection and is generally vertical. 100 When the member G³ is in contact with the projection I¹ the emergency supply valve is closed and as shown in Figure 2 the arrow points upward. When the member G³ is in contact with the projection I the arrow 105 points horizontally and the emergency supply connection is open and free to be drawn upon.

The attachment which I have invented and which has been described has, besides 110 advantages that have been pointed out, these also: the article is very simple in construc-

- tion and hence may be very easily and cheaply manufactured and besides it may be easily cleaned of sediment or other material that might tend to form a stoppage in the line 5 by removing the casting E_1 and the several fluid passages through it including others in the valve and its seat are exposed, and are relatively close to and directly in line with the several open ends of the casting, permitting 10 the interior passages to be readily wiped out and cleaned. This can be done without removing any part of the connection, it only being necessary that the several couplings, as I term E^3 , E^5 and E^7 be separated.
- 15 Although I have shown an operative device, still it will be obvious that many changes might be made in size, shape and arrangement of parts without departing materially from the spirit of my invention; and 20 I wish, therefore, that my showing be taken as in a sense diagrammatic.

The use and operation of my invention are as follows:

- 25 When it is desired to insert my valve in the fuel line of an automobile, the normal fuel connection to the tank is removed and my valve is screwed directly into the fuel outlet of the tank, the part E^3 being screwed into this outlet. The normal fuel line connection is then secured to the part E^5 of my valve, and fuel may be taken to the fuel line as usual.

30 In normal working conditions the valve will be adjusted as shown in Figures 2, 3, 35 and 4 so that the fuel drawn out of the valve and through the fuel system must pass through the top of the partition F .

- 35 The pressure escape tube H is provided 40 to prevent any siphoning action which might be set up and cause the tank to empty. When the fuel has been drawn down to the point substantially equal with the top of the partition F , further fuel withdrawal will stop. The driver may then operate the valve

to permit fuel to pass through the opening 45 of the partition—that is through the openings F^2 F^3 and the registering passage G^1 , and the fuel may then be drawn down to its lower level. Thus a reserve supply is provided in the tank without reconstruction 50 or alteration of any of the parts of the ordinary fuel supply system.

I claim:

A reserve supply attachment for fuel tanks 55 consisting of a casting having a straight tubular portion with open ends adapting it to be attached to the fuel line, and having also an intermediate vertical tubular portion disposed at right angles to the first-named tubular portion and connecting therewith intermediate its ends, a partition in the said intermediate tubular portion terminating short of the open end thereof, and forming a barrier to the fluid passage through the horizontal tubular portion, the portion of the 60 partition in the horizontal tubular part of the attachment being formed into a hollow cylindrical enlargement shaped to constitute a valve seat, such enlargement having openings 65 which are respectively beside the open ends of the horizontal portion of the attachment, a valve seated in said enlargement provided with a cross opening adapted to register with the openings through the valve seat and put them in communication with each 70 other or to intercept such communication accordingly as the valve is adjusted and a vent tube connected with the open end of the vertical tubular part of the attachment the several 75 passages through the casting and the valve being disposed opposite the open ends of the tubular parts for ready cleaning when the attachment is disconnected.

Signed at Chicago, county of Cook, and State of Illinois, this 2nd day of January, 1926.

HAROLD M. COOPER.
